UNITED STATES PATENT OFFICE.

GEORGE MCKAY, OF NORWICH, CONNECTICUT.

BRAIDING-MACHINE.

SPECIFICATION forming part of Letters Patent No. 468,225, dated February 2, 1892.

Application filed December 17, 1890. Serial No. 375,027. (No model.)

To all whom it may concern:

Be it known that I, GEORGE MCKAY, a citizen of the United States, residing at Norwich, in the county of New London and State of Connecticut, have made certain new and useful Improvements in Braiding-Machines, which improvements are fully set forth and described in the following specification, reference being had to the accompanying sheet 10 of drawings.

This invention is in that class of braiding-machines in which the various strands are carried between and around the others of the series at stated times to interlace or braid together said strands, the bobbins being carried and directed by a multiple of gears; and my object is to simplify somewhat such machines and also to reduce materially the wear of engaging parts.

With these ends in view I have produced the machine illustrated in the annexed drawings, Figure 1 being a vertical sectional view of a machine embodying my improvements, taken on line $x-x$ of Fig. 2, the latter figure 15 being a top or plan view of the carrier-disk and a portion of the surrounding internal gear, two of the carrier-gears being also shown in proper position on said disk.

The several elements of the machine are supported on or within a shell a , to the top of which is secured an internal gear b , whose teeth, it should be noted, are alike throughout the series and not mutilated at stated distances, as is usual in such machines. c denotes the carrier-disk, secured to a hollow vertical shaft, bearing at its lower end a bevel-gear d , which is driven by a corresponding gear d' on a shaft e in a manner common to this class of machines. Located on studs f on disk c are three or more gears g , that mesh with the described internal gear and are caused to rotate by the latter as disk c revolves. Gears g have a series of notches g' , adapted to fit the neck of the bobbin-carriers. Immediately beneath gears g the disk c is recessed, as at h , the outer wall of said recess being circular throughout a considerable portion and approximately in vertical alignment with the pitch-line of the gears g . The entrance to recess h —that is to say, the side nearest the periphery of disk c —is formed as

intersecting channels, that lead into and out of the recess, said channels being formed by attaching to disk c fixed switch-sections $h' h^2 h^3$, the latter being approximately triangular and so located that its apex is immediately opposite the center of gear g and serves to guide the foot of the traveler inward toward said gear when the machine is in operation. The switch-section h' is located within recess h and sections h^2 at each side of the entrance to said recess, the space or channels between sections h' and h^2 being in line with the operative sides of section h^3 , so that when the foot of the traveler is engaged and crowded inward by said section h^3 said traveler may be guided into recess h and pass around with gear g .

As here illustrated, disk c is formed with a projecting ledge c' between the described switch portions; but such ledges are not essential to the working of my machine, it only being necessary to provide at proper intervals on the periphery of said disk projecting portions sufficient to support the switch-section h^3 . When the bobbin-carriers are deposited and left in the internal gear b , they are then supported entirely by said gear until again removed by the gears g . The switches h', h^2 , and h^3 are made of steel and screwed or bolted to disk c , so that when worn they may be removed and replaced by new ones. To prevent the undue wear of the peripheral wall of recess h , I spring into said recess a steel bushing i , against which the foot of the bobbin-carrier may travel as the latter is carried around by gear g , the recess being preferably provided with shoulders, as the ends of the plates h^2 , against which the ends of the spring abut. The switch-section h^3 should be of such pitch on its inner edge that when the foot of the bobbin-carrier engages it said foot is forced inward (toward the carrier-gear) until one of the notches g' of said gear engages the traveler-neck, when it (the traveler) is carried between switch-sections $h' h^2$ and thence around with said gear, when it is again switched outward and left in one of the teeth of the internal gear b . I have stated that the teeth of the internal gear are not mutilated, as in other machines of this class. By thus being able to use a gear with uniform teeth I

may occasionally move said gear around to change its position relative to the notches g' of the carriers and so distribute the wear throughout the entire series of internal teeth, 5 instead of always using certain of said teeth, as heretofore. The plate c is also preferably provided with the channels $m m$, which curve inwardly toward the center of the plate and which afford convenient means for removing or inserting the travelers without taking the machine apart, as the rib of the traveler can be inserted in the channel and then moved outward until its neck enters one of the gears b , where it remains until it is removed by the 15 plate or switch h^3 and the gear g or until it is desired to remove it from the machine, when the channel is made to register with it, when it can be slipped into the channel and then taken out as easily as it was put in.

20 In operation as many travelers are placed in the gear b as is desired and the plate is rotated in the usual manner. As the gears g approach a traveler the switch h^3 crowds the traveler into the gear g , where it is carried around and again deposited in the gear b , the switch in the meantime passing on to the next traveler, which is crowded into the gear g , and so with each succeeding traveler. In this way each of the internal gears b can be used 25 to hold a traveler and also to assist in rotating the gears g , which could not be done with a mutilated gear, as then the travelers must always be placed in the same place in the gear. As the mutilation of the gear generally occurs 30 about every fourth tooth, it is evident that by being able to dispense with this mutilation and use every tooth, as can be done with my non-mutilated gear, the durability of the machine is increased to that extent, as after one tooth has become worn to any great extent 35 the gear is shifted in relation to the travelers so that the travelers will be deposited in a new or unworn tooth, and then after that becomes

worn it can be shifted again, and so on until all the teeth have been thus utilized for holding the travelers. 45

Inasmuch as machines of this class are well known, I have thought it unnecessary to illustrate the take-up, travelers, and tension devices. A familiar type may be seen in Patent No. 56,485, issued July 17, 1866, to James A. Bazin.

Having described my invention, I claim—

1. In a machine for making braided cord, a revoluble disk bearing carrier-gears, each 55 with a series of notches g' , in combination with an internal gear having non-mutilated teeth, said teeth serving to hold the carriers and also to rotate the gears, as described, and for the object specified. 60

2. In combination, in a cord-machine, a revoluble disk, a series of carrier-gears mounted thereon, an internal gear in mesh with said carriers, the disk being provided with a shouldered recess beneath each carrier to form a 65 path for the feet of the travelers, and a removable ring-bushing in each recess, the ends of which abut against the shoulders and hold it in place, substantially as described, and for the purpose specified. 70

3. In combination with a revoluble disk and a series of carrier-gears mounted thereon, an internal gear in mesh with said carrier-gears, said disk being recessed beneath the carrier-gears to form a path for the feet of the 75 travelers and having detachable switch-sections h' , h^2 , and h^3 , forming intersecting channels leading outward from said recess, but not continuing around the periphery of the disk, all being substantially as and for the 80 object specified.

GEORGE MCKAY.
